YARN SEVERING DEVICE FOR A CIRCULAR
KNITTING MACHINEGiorgio Billi, Viale Torricelli 23, and Vincenzo Luchi,
Via Lavilla 179, Galceti-Prato, both of Florence, Italy

Filed Feb. 15, 1961, Ser. No. 89,501

Claims priority, application Italy Feb. 16, 1960
6 Claims. (Cl. 66—145)

According to the invention there is provided a circular knitting machine having a device for severing yarn withdrawn from the feed position, said device comprising a stationary cutting edge and a driven wheel having a non-circular cutting edge cooperating with said stationary cutting edge.

More particularly, the present invention provides a circular knitting machine having a device for severing yarn withdrawn from the feed position, said device comprising two cooperating cutters, one of which is stationary and has a cutting edge extending substantially tangentially to a cylindrical surface defined about the rotary axis of the machine and containing the edge of the cover which overlies the needle cylinder, said edge extending adjacent said cover, the other cutter being formed by a wheel mounted for rotation on an axis substantially radial to said cylindrical surface and having a non-circular peripheral cutting edge, said wheel being rotated to cooperate with the stationary cutting edge in a substantially continuous scissors action to sever yarn presented between said cutting edges.

Upon raising the yarn guide, the device severs the yarn closely adjacent the last stitch formed by the yarn thereby avoiding subsequent cutting of the yarn end by hand and consequent handling of the fabric.

The invention will be better understood from the following description and the accompanying drawing, which set forth one embodiment of the invention. In the drawing,

FIG. 1 is a diagrammatic axial sectional view of a circular knitting machine showing a yarn severing device according to the present invention;

FIG. 2 is a plan view of the machine of FIG. 1;

FIGS. 3 and 4 illustrate two details respectively of the roller and the stationary cutting edge cooperating therewith in the yarn severing device.

As is diagrammatically illustrated in the accompanying drawing, the circular knitting machine has a needle cylinder 1 supporting needles 2 and yarn guides 3 are provided for feeding yarn to the needles. In the zone A where the stitch is formed and thus where the yarn is to be severed, a yarn severing device is located to sever said yarn coming from the yarn guide which has been raised to interrupt the feed. This device is located on the cover 5 of the needle cylinder which is above the rotary plate 6 carrying welt hooks. Plate 6 is rotated at the same rotational speed as the needle cylinder by a known form of drive.

The severing device comprises a projection 8 formed on a stationary ring 7, which is mounted on the cover 5, the projection 8 being provided with a cutting edge 8a substantially tangential with respect to a cylindrical surface extending about the axis of rotation and containing the periphery of the ring 7. The projection 8 is extended outwardly and upwardly and the cutting edge 8a extends along substantially the whole length of the projection.

Suitable supports 9 are located on the cover 5 and form bearings for a substantially radial shaft 10. This shaft carries, at its outer end, a wheel 11 (see FIG. 3) formed with teeth similar to those of a ratchet wheel. Each tooth has a radial edge and a peripheral cutting edge 12 extending angularly to the radial edge. These teeth, as they

2

move in succession in contact with the edge 8a, each form therewith a pair of scissors, the contact point of the co-operating edges 8a, 12 moving towards the yarn as the scissors close. The wheel 11 projects slightly below the cutting edge 8a of the stationary projection 8. A spring 13 on the shaft 10 urges the shaft axially inwardly so that the inner side of the wheel 11 on which the cutting edges 12 are formed, is pressed into contact with the fixed cutting edge 8a.

The shaft 10 is driven through a pair of bevel gears 14, 15, the gear 14 being coaxial with and driven by the plate 5 and the gear 15 being on the shaft 10. Preferably the diameter of the gear 15 is less than that of the gear 14 so that the wheel 11 will rotate at a rotational speed equal to the rotational speed of the needle cylinder 1 multiplied by the step-up gear ratio.

The disposition of the cutting edge 8a, and the inclination thereto of the cutting edges 12, and the direction of the rotation of the wheel 11 are such that as the yarn moves into the angle formed between the opposed cutting edges it is gripped and severed thereby in a scissors movement while the fabric together with the last needle which has picked up the yarn before the interruption of the feed by the raising of the yarn guide, passes in front of the severing device in the zone A. As is seen in FIG. 3, the wheel rotates in the direction f1 whilst the fabric moves in front of the wheel in the direction f2. The yarn to be severed is located in the convergent zone f3 between the cutting edge 8a and the cutting edge 12 which is approaching the edge 8a.

The length of yarn between the severed end and the yarn guide is retained by a device provided in the cover 5 of the needle cylinder. This device may comprise a pneumatic nozzle 16 in FIG. 2, which is extended in the horizontal direction adjacent the path of movement of the needles between the yarn guides and the severing device, and operates to suck in and retain by suction the severed length of the yarn extending from the yarn guide.

It will be evident that the cutting edges 12 are so inclined that as the wheel 11 rotates in the direction of the arrow f1, the point of contact of each cutting edge 12 with the cutting edge 8a is moved in the direction opposite to the arrow f2. For this purpose, the wheel 13 is formed with several steps defining teeth to provide several individual cutting edges as illustrated in the drawing, or the wheel 13 may be formed with a peripheral cutting edge having a single step. Alternatively, the cutting edge 12 may be formed with a number of steps or teeth, substantially greater than that indicated in the drawing.

The above description is given by way of example only, and numerous modifications thereto will be apparent to those skilled in the art which may be made without departing from the invention as defined in the claims appended hereto.

Whilst cutting edges are referred to herein, no distinction is intended to be drawn between cutting and shearing, or between scissoring action and shearing action.

What we claim is:

1. In a circular knitting machine having a rotatable needle cylinder carrying needles to which yarn is fed and means for withdrawing yarn from the needles, a device for severing yarn withdrawn from the needles, comprising: a stationary cutting edge, a driven wheel having a non-circular cutting edge cooperating with said stationary cutting edge to cut the yarn withdrawn from the needles, and means resiliently urging the wheel axially towards the axis of said cylinder to press the non-circular cutting edge into engagement with the stationary cutting edge.

2. In a circular knitting machine having a rotatable needle cylinder carrying needles to which yarn is fed and

means for withdrawing yarn from the needles at a pre-determined fixed position with respect to the cylinder, a device for severing yarn withdrawn from the needles at said position, comprising: cutting means having a stationary cutting edge, a rotatably driven wheel having a series of teeth, each of said teeth having a radial edge and a peripheral cutting edge angularly disposed to the radial edge and extending from the outermost point of the radial edge angularly inward toward the axis of the wheel, and means resiliently urging said wheel axially inward toward said cutting means to engage the cutting edges of the teeth with the stationary cutting edge as the wheel is rotated, whereby all yarns drawn between the stationary cutting edge and a peripheral cutting edge engaged therewith are instantly severed.

3. A device according to claim 2, wherein the stationary cutting edge is longer than each of the peripheral cutting edges of the wheel so that one of the peripheral cutting edges is always in engagement with the stationary cutting edge.

4. In a circular knitting machine having a rotatable needle cylinder carrying needles to which yarn is fed and means for withdrawing yarn from the needles at a pre-determined fixed position with respect to the cylinder, comprising: cutting two cooperating cutters, one of said cutters having a stationary cutting edge extending in a plane parallel to another plane tangential to said cylinder and parallel to the axis of the cylinder, the other cutter including a rotatable wheel, means rotating the wheel on an axis perpendicular to the axis of the cylinder, said wheel having a non-circular peripheral cutting edge extending all around the wheel, and resilient means urging said peripheral cutting edge into continuous contact with the stationary cutting edge to sever all yarns presented between the engaged cutting edges.

5. In a circular knitting machine having a rotatable needle cylinder carrying needles to which yarn is fed and means for withdrawing yarn from the needles at a pre-determined fixed position with respect to the cylinder,

5

comprising: cutting two cooperating cutters, one of said cutters having a stationary cutting edge extending in a plane parallel to another plane tangential to said cylinder and parallel to the axis of the cylinder, the other cutter including a rotatable wheel, means rotating the wheel on an axis perpendicular to the axis of the cylinder, said wheel having a peripheral series of teeth, each of the teeth having a radial edge and a peripheral cutting edge angularly disposed to the radial edge and extending from the outermost point of the radial edge angularly inward toward the axis of the wheel, and means resiliently urging said wheel axially inward toward said stationary cutting edge to engage the cutting edges of the teeth with the stationary cutting edge as the wheel is rotated, said stationary cutting edge being longer than each of the peripheral cutting edges so that one of the peripheral cutting edges is always in engagement with the stationary cutting edge, whereby all yarn drawn between the stationary cutting edge and a peripheral cutting edge engaged therewith is instantly severed.

10

6. In a circular knitting machine having a rotatable needle cylinder carrying needles to which yarn is fed and means for withdrawing yarn from the needles, a device for severing yarn withdrawn from the needles, comprising: a stationary cutting edge, a rotatably driven wheel having a peripheral cutting edge cooperating with said stationary cutting edge to cut the yarn withdrawn from the needles, and means resiliently urging the wheel axially toward the axis of said cylinder to press the peripheral cutting edge into continuous contact with the stationary cutting edge as the wheel is rotated.
